UNITED STATES PATENT OFFICE.

MARCUS LOEWENTHAL, OF NEW YORK, N. Y.

THREAD-MEASURING ATTACHMENT FOR SEWING-MACHINES.

SPECIFICATION forming part of Letters Patent No. 423,786, dated March 18, 1890.

Application filed August 21, 1889. Serial No. 321,502. (No model.)

To all whom it may concern:

Be it known that I, MARCUS LOEWENTHAL, a citizen of the United States, residing at New York, in the county and State of New York, 5 have invented a certain new and useful Improvement in Measuring Attachments for Sewing and Similar Machines, of which the following is a specification.

The invention consists in the construction 10 and novel arrangement of parts, as herein-after set forth.

The object is to provide a device for automatically registering the amount of material—such as thread, cord, braid, &c.—con- 15 sumed in the manufacture of garments.

In the present instance I have shown the device as attached to a sewing-machine; but it is to be understood that I may attach the device to a knitting or similar machine.

20 In the accompanying drawings, Figure 1 shows my invention as attached to a sewing-machine. Fig. 2 is a front view of the device, partly in section through the line $x-x$, Fig. 1. Fig. 3 is a top view. Fig. 4 is a longitudinal 25 section of the registering mechanism. Fig. 5 is a transverse section of the registering mechanism; and Fig. 6 is a modification of the driving-wheel, having its groove arranged for braid or other material having a greater width 30 than thickness.

Similar letters of reference designate corresponding parts in all the figures.

Referring by letter to the drawings, A designates the arm of a sewing-machine, and 35 A' is a tension device thereon. As the sewing-machine and tension device may be of any well-known construction, it is not deemed necessary to illustrate or describe the mechanism thereof.

40 B designates the grooved driving or main wheel secured on and rotating with a shaft a, which is journaled in a boxing a' on a bracket B', secured to the machine-arm A. The wheel B may be removably secured to 45 the shaft a in any well-known manner. I have here shown it as having one end of its hub butted against a collar b, fixed on the shaft a, and a clamping-nut b' butting against the other end of the hub and engaging a 50 threaded portion of the shaft a. One end of the shaft a is provided with a worm a², en-

gaging with a toothed wheel C, which rotates the registering-wheels, as hereinafter explained.

D is a supply-spool of thread, cord, or braid 55 loosely rotating on a spindle d, projecting from the bracket B'. From this spool D the thread or other material is carried once or more around the wheel B within the groove, thence through the tension A' to the goods 60 operated upon.

As it is preferable to supply the thread to the wheel B under an even tension, or, in other words, prevent looping or sagging of the thread between the supply-spool and wheel, I provide 65 a tension device in connection therewith. The tension device here employed consists of a weight c, having an arm c', pivoted to the bracket B'. It is obvious that the weight, which is preferably ball-shaped, will bear with 70 a slight friction upon the thread and follow toward the spool-shank as the thread is unwound.

The registering mechanism here employed or shown is of an ordinary construction used 75 in so-called "adding-machines," and it is to be understood that I do not limit myself to any specific form of registering mechanism. The registering mechanism here shown may be described as follows: E designates a suitable 80 case or box mounted on the bracket B', and e e' e² e³ e⁴ e⁵ e⁶ are registering wheels or disks mounted on a shaft c² within the case. It will be seen that the toothed wheel C is rigidly mounted on the outer end of the shaft c², and 85 the disk e is also rigidly mounted on this shaft, the other disks being loosely mounted thereon. Each disk has on its periphery ordinals from 0 to 9, inclusive, and the wheel B, the worm a², and the wheel C bear such relation to each other that nine yards of thread 90 or other material passing over the wheel B will rotate the disk e until the ordinal 9 is visible through the sight-opening in the case E. During the revolution of the disk e, as 95 above indicated, the other disks remain idle or with 0 showing. When one more yard, however, has passed over the wheel B, the disk e engages with the disk e' and moves with it one step, so that ten yards are indicated through the sight-opening, and the disks e², &c., remain idle till the disk e' shall have 100

made a complete revolution, or indicates 99, and then the next disk is set in motion.

It is obvious that I may duplicate the whole mechanism employed, so that both thread and braid may be measured during the operation of braiding patterns on goods.

I have employed the term "yards;" but it is to be understood that the mechanism may be so constructed as to register other measure of length.

What I claim as my invention, and desire to secure by Letters Patent, is—

The combination, with a sewing-machine and a tension thereon, of a thread-supply, a tension therefor, a wheel arranged between the supply and tension first named, over which thread may run, and a registering mechanism connecting with said wheel, substantially as specified.

MARCUS LOEWENTHAL.
